UNITED STATES PATENT OFFICE.

ALPHONSE FERNANDEZ, OF WASHINGTON, DISTRICT OF COLUMBIA.

DETACHABLE ARMORED SECTION FOR SUBMARINES.

1,235,781.

Specification of Letters Patent.

Patented Aug. 7, 1917.

Application filed September 20, 1916. Serial No. 121,246.

To all whom it may concern:

Be it known that I, ALPHONSE FERNANDEZ, a subject of the King of Spain, residing at the city of Washington, in the District of Columbia, have invented certain new and useful Improvements in Detachable Armored Sections for Submarines; and I do declare the following to be a full, clear, and exact description of the invention, such as will enable others skilled in the art to which it appertains to make and use the same.

My invention aims to provide a submarine having a detachable upper section in which all of the armament with the exception of the torpedo tubes is located, means being employed whereby said section may be cast off at will in case it is injured by gun fire, bombs dropped from airships, or by mines, thus insuring that the added weight of water entering said section will not capsize the entire vessel.

With the foregoing general object in view, the invention resides in certain novel features of construction and in unique combinations of parts to be hereinafter fully described and claimed, the descriptive matter being supplemented by the accompanying drawings which constitute a part of this application and in which:

Figure 1 is a side elevation, partly in section, of the improved submarine;

Fig. 2 is a horizontal section on the plane of the line 2—2 of Fig. 1, looking in the direction of the arrows;

Fig. 3 is a vertical transverse section on the plane of the line 3—3 of Fig. 1;

Fig. 4 is a similar view showing the manner in which the detachable top section may be cast off;

Figs. 5 and 6 are detail longitudinal sections on the planes designated by the lines 5—5 and 6—6 of Fig. 3;

Fig. 7 is a detail transverse section on the plane designated by the line 7—7 of Fig. 6.

In the drawings above briefly described, the numeral 1 designates the shell of the improved submarine which carries the usual submerging and propelling means, the torpedo tubes, air supply tanks, etc., while the numeral 2 designates a detachable top section designed to carry practically all of the armament. When the improved vessel is constructed for light duty such as the guarding of coasts or harbors having water of

sufficient depth to permit submerging, the ship may be rather small and need not be armed and armored as heavily as when it is adapted for instance, to travel from one country to another and bombard cities or forts at the latter with a chance of encountering enemy battleships on the way.

In most instances, the top of the shell 1 and the bottom of the section 2 will be flat and the sides of said section will be equipped with depending outwardly inclined flanges 3 to abut shoulders 4 on said top of the shell to assist in preventing lateral shifting of the detachable section. Vertical screws 5 and quickly releasable devices 6 are provided for holding the section 2 in operative position upon the shell 1 but all lateral strain will obviously be removed from these parts by the flanges 3 and shoulders 4.

The screws 5 are provided on their inner ends with bevel gears 7 located on the interior of the shell 1, said gears meshing with similar gears 8 and a pair of longitudinal shafts 9 said shafts being revolubly mounted in bearings 10 which are slidably supported by brackets 11 depending from the top of the shell 1, springs 12 being disposed beneath said bearings to normally support them but to permit the same to move downwardly as both shafts 9 must necessarily descend when the screws 5 are released. The shafts 9 may be provided on their ends with hand wheels 13 or other suitable means may be used for rotating said shaft for the purpose of releasing the screws.

The devices 6 consist of vertical shafts 14 carried rotatably by and projecting above the shell 1 and equipped with cross heads 15 on their upper ends which are adapted, when turned to the proper extent, to register with slots 16 in the bottom of the section 2, whereby, with the screws 5 released the entire upper section will be disconnected from the shell 1. For simultaneously turning all of the shafts 14 they are preferably provided with crank arms 17 pivoted to a single operating rod 18 which extends longitudinally of the ship, and when the devices 6 are turned to released position, coiled springs 19 will retract them as shown in Fig. 4 so as to permit the entire armament section 2 to slide from the body of the vessel. Under normal conditions with the

parts standing as shown in Fig. 3, strain is relieved from the springs 19 by means of casings 19^a which surround such springs.

In use, when it is seen that the submarine 5 is in danger of having its upper quarters injured by shell fire, bombs or mines, the hand wheels 13 are rotated to release all of the screws 5, thus leaving the devices 6 as the entire means of connecting the upper section 10 2 with the shell 1. Should said section 2 be now so injured as to cause flooding thereof, the added weight will cause the entire vessel to list as shown in Fig. 4, but the moment it is observed that such listing is 15 taking place, the rod 18 is operated to release all of the devices 6, whereupon when the ship has tilted a predetermined amount, the section 2 will slide from the remainder of the craft as indicated in Fig. 4. The section 20 2 when detached will of course sink and its contents will be lost unless recovered in the future, but the body of the vessel and the lives therein will be saved. It will thus be obvious that the main body of the ship 25 is fit for further use and may discharge torpedoes whenever expedient.

From the foregoing, taken in connection with the accompanying drawings, it will be observed that although the invention is of 30 simple nature, it will fulfil a long felt need. Certain specific details have been shown and described for accomplishing probably the best results, but it is to be understood, however, that within the scope of the invention 35 as claimed, numerous changes may be made without sacrificing the principal advantages.

I claim:

1. A submarine comprising a body sec-

tion, an upper section resting thereon, and 40 means operable from the interior of the body section for holding the two sections together under normal conditions and for totally disconnecting them in case said upper section is injured, whereby said upper 45 section may sink without carrying with it the body section.

2. A submarine comprising a main body section, a detachable upper section resting thereon, means for holding the two sections 50 together, and quickly releasable fastening means for holding the upper section on the lower after the aforesaid means have been released.

3. A submarine comprising a main body 55 section, a detachable upper section resting thereon, a plurality of screws for securing the two sections detachably together, bevel gears on the lower ends of said screws and located in said main body section, a longitudinal operating shaft having bevel gears meshing with the aforesaid gears for simultaneously releasing all of the screws when said shaft is rotated, bearings for said shaft, brackets in which said bearings are mounted 60 65 for vertical sliding, and springs carried by said brackets for exerting an upward thrust on said bearings but for permitting them to move downwardly with the operating shaft as the screws are released.

In testimony whereof I have hereunto set my hand in the presence of two subscribing witnesses.

ALPHONSE FERNANDEZ.
